UNITED STATES PATENT OFFICE

JAMES E. SAPP, OF BAINBRIDGE, GEORGIA, ASSIGNOR TO RICH MANUFACTURING COMPANY, OF BAINBRIDGE, GEORGIA

REFRIGERATOR

Application filed August 8, 1928. Serial No. 298,345.

This invention relates to refrigerators, and has more particular reference to an improved refrigerator adapted to be easily and quickly converted into a dry cold storage refrigerator, a bottle dispensing refrigerator, or a combination dry cold storage refrigerator and bottle dispensing refrigerator.

An important object of the present invention is to provide a refrigerator embodying removable parts which may be readily replaced by new ones should they become worn or damaged from any cause.

Still another object is to provide a refrigerator embodying removable bottle dispensing and dry cold storage units that may be associated in different relations to provide an ice compartment of the desired size and location as dictated by special requirements, and which may be entirely removed to permit use of the refrigerator as an ice chest.

Other objects are to provide for maximum cooling efficiency, convenience in manufacture and use, and maximum capacity for bottled goods to be cooled and dispensed.

The invention consists in the novel form, combination and arrangement of parts hereinafter more fully described, shown in the accompanying drawings and claimed.

In the drawings:

Figure 1 is a top plan view of a refrigerator embodying the present invention.

Figure 2 is a vertical longitudinal section thereof on line 2-2 of Figure 1.

Figure 3 is a view of the refrigerator shown in Figure 1, partly in horizontal section and partly in top plan.

Figure 4 is a vertical transverse section on line 4-4 of Figure 2.

Figure 5 is a perspective view of one of the bottle dispensing units.

Figure 6 is an enlarged view, partly in side elevation and partly broken away and in section, of a modified form of bottle dispensing unit.

Figure 7 is a top plan view of the device shown in Figure 6; and

Figure 8 is a vertical section on line 8-8 of Figure 6.

The embodiment of the invention shown in Figures 1 to 5 inclusive of the accom-

panying drawings consists of a suitable frame 5 having corner supporting legs 6 and in which is mounted a rectangular box 7 which is open at the top and has sides, ends and a bottom of double wall construction with insulation 8 between the walls thereof as clearly illustrated in Figures 2 to 4 inclusive.

The walls of the box 7 are preferably of wood and provided with a sheet metal covering 9, while a sheet metal tub 10 is fitted in the box 7 to extend from end to end thereof, said tub 10 having a round or cylindrical bottom portion resting centrally upon the bottom of the box 7 and spaced from the lower corners of the latter to provide air spaces as clearly shown in Figure 4. It is particularly noted that the tub 10 is removably fitted in the box so that it may be replaced by a new one when worn or damaged, the tub being retained in place by suitable means such as a sheet metal molding 11 fitted over the upper edges of the ends and sides of the box 7 and the upper marginal portions of the sheet metal covering 9 and the tub 10. The molding 11 is removably secured in place by means of screws 12 or the like driven into the walls of the box 7 as shown.

A plurality of article receiving compartments or units are removably fitted in the tub 10, and two of these are illustrated as embodying bottle holding and dispensing units generally denoted by the reference character 13, while the remaining compartment 14 consists of an open top imperforate receptacle adapted for receiving goods which may be desired to be kept cool but which cannot be submerged in the cooling fluid placed in the tub 10. It will be noted that the combined widths of the compartments is less than the total length of the tub 10, thereby leaving an intervening space as at 15 constituting an ice chamber. Obviously, the ice chamber may be provided at any point in the tub by properly positioning the compartments or removable units, while elimination of any one or more of the compartments or units will result in a corresponding increase in size of the ice chamber. On the other hand, the receptacle 14 may be replaced by a bottle holding and dispensing unit 13 to make the refriger-

erator wholly a bottle dispensing refrigerator, or a compartment 14 of any desired size may be used in the absence of bottle holding and dispensing units to thereby make the refrigerator strictly a cold storage dry refrigerator.

Each bottle holding and dispensing unit 13 consists of an open top receptacle shaped to snugly fit within a portion of the tub 10 and provided with spaced U-shaped partitions 16 disposed in nested relation to form a plurality of channels of substantially semi-cylindrical form so as to accommodate the bottles 17 in horizontal side by side relation as illustrated clearly in Figures 2 to 4 inclusive. The bottle dispensing units 13 are suitably perforated as at 18 to permit the cooling fluid to freely pass into and fill the bottle channels to the required level. Obviously, the tub 10 and the units 13 may be of any desired size to provide for more than two channels in each bottle dispensing unit, but the units are shown as each embodying two such channels for purposes of illustration. Moreover, the space between the legs of the innermost partition 16 of each unit 13 is utilized for receiving a row of bottles as at 17^a in an upright side by side relation. The space or compartment in which the bottles are placed at 17^a may be imperforate to provide for dry cooling of the bottled goods at this point, or the units 13 may be perforated to also permit the cooling fluid to enter the compartment for the bottles at 17^a if preferred. Obviously, the bottles at 17 are adapted to be passed through the channels of the units 13, each bottle being inserted in the channel at one end and being forced through the channel and out the other end by the insertion of succeeding bottles.

The top of the box 7 is closed by means of a removable cover consisting of a plurality of sections, each of which forms a lid for a separate unit or compartment 13 or 14 or for the ice chamber 15. As shown, the cover consists of a section 19 forming a lid for the ice chamber 15 and having sections 20 hinged to opposite sides thereof as at 21 to respectively form lids for the bottle holding and dispensing units 13 disposed at opposite sides of the ice chamber. A further relatively narrow cover section 22 has a wider lid-forming section 23 hinged to one side thereof as at 24 to form a closure for the dry storage compartment 14. It is particularly noted that the units or compartments 13 and 14 are of similar width, thereby enabling the cover sections to be made of corresponding width for interchangeable use in accordance with the manner in which the units or compartments 13 and 14 are placed or associated in the tub 10. Each cover section has a lining 24 of insulating material adapted to fit within the top of the box 7 to effectively exclude the entrance of warm air into the refrigerator, and

one side wall of each unit 13 or compartment 14 has an upward extension 26 adapted to fit between the adjacent edges of the lining 25 of adjacent cover sections so as to prevent passage of warm air into any compartment or unit when the cover section or lid of an adjacent compartment or unit is opened.

A suitable display rack 27 is detachably mounted upon the back of the box 7 to receive bottles as at 17^b. The latter bottles will thus be positioned and displayed in an orderly manner as well as located for convenient access when desired to be placed into the channels of the bottle holding and dispensing units 13, it being understood that a bottle is inserted at one end of each channel whenever it is desired to dispense a bottle from that channel at the other end.

From the above description it will be apparent that the units or compartments 13 and 14 may be used in such number and relation as to provide a refrigerator suitable for various requirements. For example, the number of units 13 may be varied to obtain the desired capacity in connection with the size of the box 7 and the number of channels provided in each unit 13. Moreover, the number of units 13 may be varied to change the size of the ice chamber 15. These are simply a few of the many combinations which may be effected by varying the size, location and number of the units 13 and compartments 14 respectively employed. Other variations will be apparent or suggest themselves to those skilled in the art, while the ready removal of parts will be at once apparent as well as the advantage of ready renewal of parts to be derived therefrom.

Minor changes may be made without departing from the spirit and scope of the invention as claimed.

Bottle dispensing units of the form shown in Figures 6 to 8 inclusive may be substituted for the units 13 of Figures 1 to 5 inclusive whenever it is desired to restrict use of the refrigerator for cooling and dispensing the goods of any particular merchant using bottles of a distinctive or special longitudinal contour of irregular form. In this instance, the open-top unit 13^a has side walls connected by spaced pairs of nested U-shaped walls or partitions 16^a corrugated longitudinally to form channels conforming in cross-sectional shape to the opposite sides of the bottles 17^a to be passed therethrough in horizontal side by side relation. The walls in this embodiment are suitably perforated as at 18^a to permit the cooling liquid to enter and fill the channels to the desired level.

What I claim as new is:

1. In a refrigerator of the character described, a rectangular box having a round bottom tub removably fitted in and extending from end to end thereof, a plurality of round

- bottom commodity compartments removably fitted in said tub, and a cover for said box composed of a plurality of sections, each providing a lid for a separate one of said compartments, one side wall of each compartment having an upward extension, and each section of the cover having an inner lining of insulating material adapted to cooperate with the wall extensions of the compartments to exclude entrance of air into one compartment when the cover section of an adjacent compartment is opened.
2. In a refrigerator of the character described, a rectangular box having a round bottom tub fitted in and extending from end to end thereof, and a plurality of round bottom commodity compartments removably fitted in said tub in side by side relation, certain of said compartments comprising bottle holding and dispensing units spaced to provide an ice chamber therebetween, each bottle holding and dispensing unit consisting of an open top perforated receptacle having spaced nested U-shaped partitions forming a plurality of channels through which bottles are adapted to be passed in horizontal side by side relation, another of said compartments comprising an open-top imperforate receptacle devoid of partitions.
3. In a refrigerator of the character described, a rectangular box having a round bottom tub fitted in and extending from end to end thereof, and a plurality of round bottom commodity compartments removably fitted in said tub, certain of said compartments comprising bottle holding and dispensing units, each bottle holding and dispensing unit consisting of an open top receptacle having a plurality of spaced U-shaped partitions defining channels through which the bottles are adapted to be passed in horizontal side by side relation, the space between the legs of the innermost partition forming a compartment for reception of a row of upright bottles in side by side relation.
4. In a refrigerator of the character described, a rectangular box having a round bottom tub removably fitted in and extending from end to end thereof, and a plurality of round bottom commodity compartments removably fitted in said tub, certain of said compartments comprising bottle dispensing units embodying receptacles having spaced nested partitions forming channels through which the bottles are adapted to be passed in horizontal side by side relation, and said receptacles being perforated to permit entrance of cooling fluid therein.
5. In a refrigerator of the character described, a rectangular box having a round bottom tub removably fitted in and extending from end to end thereof, and a plurality of round bottom commodity compartments removably fitted in said tub in side by side relation, certain of said compartments comprising bottle dispensing units having channels through which the bottles are adapted to be passed in horizontal side by side relation and perforated to permit entrance of cooling fluid therein, and another of said compartments comprising an open top imperforate receptacle for the dry cold storage of goods.
6. In a refrigerator of the character described, a rectangular box having a round bottom tub removably fitted in and extending from end to end thereof, and a plurality of round bottom commodity compartments removably fitted in said tub, certain of said compartments comprising bottle holding and dispensing units, each bottle holding and dispensing unit consisting of an open top receptacle having spaced nested U-shaped partitions forming a plurality of channels through which bottles are adapted to be passed in horizontal side by side relation, and each latter compartment being perforated for the free entrance of cooling liquid therein, said partitions being arranged in pairs and corrugated longitudinally to define said channels of a cross-sectional shape conforming to the opposite sides of bottles having an irregular longitudinal contour.
7. In a refrigerator of the character described, a bottle dispensing unit consisting of an open-top receptacle having spaced pairs of nested U-shaped walls defining a plurality of channels through which bottles are adapted to be passed in horizontal side by side relation, said walls being longitudinally corrugated to define the channels of a cross-sectional shape conforming to the opposite sides of bottles having an irregular longitudinal contour.
- In testimony whereof I affix my signature.
- JAMES E. SAPP.
